JOURNAL BOX LUBRICATING PAD

George W. Ditmore, Albany, N. Y.

Application April 26, 1935, Serial No. 18,442

9 Claims. (Cl. 308—88)

The present invention relates to pads adapted for use in railway car truck journal boxes, for supplying lubricant to the journals of truck axles located in such boxes.

The invention contemplates the provision of a simple and efficient unitary pad of the type described which is inexpensive to fabricate and easy to apply. Heretofore, and despite the fact that it has been suggested from time to time that unitary lubricating pads might be advantageously employed, it is still customary practice to insert quantities of loose cotton waste in car truck journal boxes, the waste being placed between the rotating journal and the bottom of the box, thus becoming saturated with the oil which is also placed in the journal box and conducting this oil to the surface of the journal. Even when frequent inspections are made and the cotton waste replaced or added to from time to time "hot boxes" resulting from an interruption of the supply to the rotating journal are of not infrequent occurrence. The loose waste has also other disadvantages which are fully appreciated by those familiar with the problems of railroad rolling stock maintenance.

In accordance with the present invention a very simple type of pad is provided, this pad being a unitary structure insertable into the space which is ordinarily occupied by the cotton waste previously referred to and being so designed and constructed that it tends to expand upwardly to maintain continuous contact with the lower surface of the rotating journal. The design of the pad is such that it may not "roll" within the journal box despite the action of the rotating journal and is fabricated of material which is not only well adapted to conduct oil but possesses a considerable springiness or resiliency while at the same time is moderate in cost. Preferably the material which I employ is relatively thick sheet felt, but it will be appreciated that the invention is not limited with respect to the material actually used.

In the accompanying drawing several forms of the invention are illustrated by way of example:

Figure 1 illustrates in perspective one of the several proposed embodiments of the improved lubricating pad;

Figure 2 shows the same pad in cross section after having been inserted in a journal box, which box is also shown in cross section;

Figure 3 is a longitudinal vertical section through a journal box in which this form of pad has been inserted;

Figures 4 and 5 are views similar to Figures 1 and 2, respectively, but showing a different form of the invention in perspective and in section;

Figures 6 and 7 show a third form of the pad in perspective and in section; and

Figures 8 and 9 show a still further form of pad constructed in accordance with the invention, in perspective and section respectively.

The pad shown in Figures 1, 2, and 3 comprises a single sheet of relatively thick, springy, or resilient felt, indicated at 10. The mid-portion of the felt sheet is curved to form a tube and portions thereof parallel to the axis of the tube and equally spaced from the edges thereof are suitably secured together as by means of stitching 11 or by any other kind of securing means, for instance metallic staples. The ends of the sheet lying within the tubular portion 10 are reversely curved, that is, curved away from each other as shown, and have their ends preferably in contact with the inner wall of the tubular section.

Prior to insertion in a journal box the pad is generally oval in cross section but after insertion, in which insertion it is vertically compressed in order that it may enter the space under the journal 12, the pad has the cross section shown in Figure 2, the upper portion of the tube 10 being depressed and the end portions of the sheet which lie within the tubular portion 10 occupying the positions in which they are shown, the upper surfaces of these end portions closely contacting with the inner wall of the tube 10 and the ends thereof preferably bearing against the inner wall of tube 10 as shown. The ends of the sheet which lie within tube 10 provide what may be designated as a resilient interior structure which reinforces the pad and supports that portion of the tube 10 which rests against the journal 12, supplementing the natural resiliency of the wall of tube 10 and maintaining this wall tightly pressed against the journal at all times.

The resilient inner structure may be formed in various ways. In Figures 4 and 5 of the drawing, I disclose an inner member 13 arched in transverse section, the ends of which are secured, as by stitches 14, to the inner wall of the felt tube 15. Tube 15 comprises a rectangular sheet of felt having its ends secured together as by stitches 16. When the pad in question is inserted in a journal box and is vertically compressed, the uppermost portion of the arched member 13, which in this instance comprises the inner reinforcing structure, is engaged and distorted by the inner wall of that portion of the outer tube 15 which

is deflected downwardly to the greatest extent and exerts a constant pressure upon this portion of the outer tube in an upward direction, maintaining the same at all times in contact with the journal. If desired, the longitudinal edges of the arch member 13 may be provided with projecting portions 17 which extend through suitable apertures formed in the wall of the tubular member 15, thus more firmly securing the two parts of the pad together and preventing displacement of the ends of the arch member 13 relatively to the wall of the tube 15.

In the form of the invention shown in Figures 6 and 7 the outer member 18 is formed as a continuous felt tube and likewise the inner supporting core or structure 19. The inner tube 19 is secured to the outer tube 18 at spaced points, as by lines of stitching 20, so that substantial areas of these tubes are always in mutual contact, this portion of the pad having in reality a double wall. When inserted within a journal box the pad is vertically compressed as shown in Figure 7 and exerts a substantial pressure against the bottom of the journal.

In the form of the invention shown in Figures 8 and 9 the outer tube 22 is formed in two portions 23 and 24 the edges of which are secured together, as by stitching 25. The ends of the arch-like inner member 26 are secured to the upper surface of the smaller member 23, along the margins thereof, as by stitching 27, this attachment being effected, preferably, prior to securing the members 23 and 24 together. Arch member 26 may or may not have projecting lugs passing through suitable apertures formed in the element 23, as desired. When placed in a journal box, arch 26 resiliently supports that portion of the tube 24 which is in immediate contact with the journal 28.

In all forms of the invention the inner core or supporting structure not only comprises means for pressing portion of the outer tube against the journal but likewise comprises a bracing or stiffening means for one side of the outer tube, having the effect of so supporting or bracing this tube interiorly that it may not "roll" in the journal box under the action of the rotating journal. The inner supporting cores may be formed in other ways but, as will be understood, will function in each instance to not only so brace the outer tube as to prevent its rolling in the journal box but also to resiliently support that portion of the tube which contacts with the journal. In each instance a tab is provided, projecting from the end of the pad, and by means of which it may be readily grasped as by a hook or other tool and withdrawn from the journal box for the purpose of inspection and repair or replacement if injured or worn out. One of these tabs is illustrated in each of the perspective views, though not specifically described inasmuch as any suitable device capable of being grasped or engaged by a tool may be made use of.

Having thus described the invention, what is claimed as new and desired to be secured by Letters Patent is:

1. A pad adapted for use in a railroad car truck journal box for supplying lubricant to the journal of an axle, said pad comprising a single curved sheet of springy oil conducting material, longitudinally extending portions thereof remote from the ends being secured together, and the end portions being confined within the tube thus formed.

2. The combination set forth in claim 1 in

which the free ends of the sheet are curved away from each other and the end edges lie adjacent the inner surface of the wall of the tube.

3. A pad adapted for use in the journal box of a railroad car truck for supplying lubricant to the journal of an axle, said pad comprising an outer tube of relatively thick felt or like oil conducting springy sheet material, and an inner arch of the same material, said arch having its ends secured to the inner wall of the outer tube.

4. The combination set forth in claim 3 in which the wall of the outer tube is provided with spaced apertures, the ends of the inner arch projecting through said apertures.

5. A pad adapted for use in a journal box of a railroad car truck for supplying lubricant to the journal of an axle, said pad comprising a tube of relatively thick felt or like oil conducting springy sheet material, said tube being transversely compressible so as to be insertable between a journal and the wall of a journal box and having within the same a longitudinally extending core of the same material, said core having portions permanently attached to the tube and portions bowed away from the wall of said tube and normally out of contact therewith, said core being compressed only when the tube is transversely compressed, and then serving to yieldingly urge the outer surface of the tube against the journal and to prevent rolling of the tube under the action of the rotating journal.

6. A pad adapted for use in a journal box of a railroad car truck for supplying lubricant to the journal of an axle, said pad comprising a tube of relatively thick felt or like oil conducting springy sheet material, said tube being transversely compressible so as to be insertable between a journal and the wall of a journal box and having within the same a longitudinally extending core of the same material, said core having portions attached to the tube and portions arched away from the wall of said tube and normally out of contact therewith, said core being compressed only when the tube is transversely compressed, and then serving as the sole means, aside from any inherent resistance of the material of the tube, for yieldingly urging the outer surface of the tube against the journal and to prevent rolling of the tube under the action of the rotating journal.

7. A pad adapted for use in the journal box of a railroad car truck for supplying the lubricant to the journal of an axle, said pad comprising an outer tubular member of relatively thick felt or like oil conducting springy material, said tube being transversely compressible so as to be insertable between a journal and the wall of the journal box, an inner tubular member of the same material as the first named member, said inner tubular member being of a smaller diameter than said first named member and disposed eccentrically thereto, one side of the inner tubular member being secured to the inner wall of the outer tubular member at a point remote from said journal and adjacent said journal box wall.

8. The combination set forth in claim 7 in which, when the pad is applied to a journal box, the respective centers of said tubular members and the center of the journal box lie in a straight line.

9. A pad adapted for use in a journal box of a railroad car truck for supplying lubricant to the journal of an axle, said pad comprising a tube of relatively thick felt or like oil conducting springy sheet material, said tube being trans-

versely compressible so as to be insertable between a journal and the wall of a journal box and having within the same a longitudinally extending core of similar material, said core having 5 portions attached to the tube at the journal box contacting wall thereof, and portions extending toward the journal contacting wall of the tube but out of contact therewith when undistorted as when removed from the journal box and 10 brought into contact with the tube only when

the tube is transversely compressed for insertion, the area of contact between the core and the journal contacting wall of the tube being of considerable extent when the pad is thus compressed and disposed directly below said journal, said core then serving to yieldingly urge the outer surface of the tube against the journal and to prevent 5 rolling of the tube under the action of the rotating journal.

GEORGE W. DITMORE. 10
